UNITED STATES PATENT OFFICE.

MICHAEL A. ZINNIEL, OF FREEPORT, MINNESOTA.

WHEELBARROW.

1,411,322.

Specification of Letters Patent. Patented Apr. 4, 1922.

Application filed July 14, 1920. Serial No. 396,315.

To all whom it may concern:

Be it known that I, MICHAEL A. ZINNIEL, a citizen of the United States, residing at Freeport, in the county of Stearns, State of Minnesota, have invented certain new and useful Improvements in Wheelbarrows; and I do hereby declare the following to be a full, clear, and exact description of the invention, such as will enable others skilled in the art to which it appertains to make and use the same.

This invention relates to new and useful improvements in wheel barrows, and has for its primary object to provide a device of this character which is operable to discharge the load carried thereby.

A further object of the invention is to provide a device of this character in which the bottom of the wheel barrow is adapted to automatically deposit the material supported thereby under the influence of the weight of said material.

A further object of the invention is to provide novel means for maintaining the body in its closed position against the action of the weight of the material supported by said body.

Referring to the drawings:

Figure 1 is a side elevation of the device in its dumping position,

Figure 2 is a transverse section on the line 2—2 of Figure 1 with the device in its closed position,

Figure 3 is a longitudinal section on the line 3—3 of Figure 2 showing the device in its closed position,

Figure 4 is a rear end elevation showing the position of the parts when the bottom is in closed position,

Figure 5 is a similar view showing the position of the parts when the device is in the dumping position,

Figure 6 is a bottom plan view of the device in closed position,

Figure 7 is a detail view of one of the bottom supporting boards, and

Figure 8 is a detail view of the forward transversely extending beam or frame member.

Referring more particularly to the drawings, the device comprises a rectangular frame 10, the side members 11 of which are connected by a forward transversely extending brace 12, and a rear transversely extending brace 13, each of said braces being

spaced a suitable distance from the respective ends of the side members 11. Depending from the edge of the side members 11 near the rear ends thereof are legs 14, while the forward ends of the side members are provided with bearing blocks 15 in which is suitably mounted a shaft or the like 16 and secured to which are the spaced wheels 17.

Projecting upwardly from the side members are side boards 18 which are connected at their ends by end boards or the like 18 and 19, the end board 19 being movably retained in place.

Rigidly secured to each of the side members 11 of the frame are brackets 20, there being one pair of brackets for each side member 11, and supported in said brackets is a longitudinally extending shaft or the like 21. Bottom boards 22 are provided on their under face with strap members 23, the free ends of which are bent around the longitudinal shafts 21 to provide means by which the bottom boards 22 are pivotally mounted on the side members 11 of the rectangular frame.

Rigidly secured to the forward transversely extending brace 12 and depending from the under face thereof is a pair of spaced brackets 24, and connecting the leg members 14 is a transversely extending brace 25, the upper edge of which is provided with bearings 26, which latter are in longitudinal alinement with bearings 27 in the bracket 24.

The bottom boards 22 are supported in their closed position by means of crank members 28 and as shown in Figure 3 these members are provided with a portion 29 which is adapted to be received within the brackets 24. Extending from the bracket 24 engaging portion 29 of each of the crank members is a right angular projection 30 and extending from said right angular projection 30 is a right angular portion 31, which lies in a plane parallel with its respective bottom board 22 and extends throughout the length of said bottom board. The crank member 28 is then bent to form a right angular portion 32 from which projects a right angular portion 33, which latter is adapted for engagement within its respective bearings 26 in the transversely extending leg brace 25, and projecting from said right angular portion 33 is a right angular portion 34 which terminates in a right

angular crank 35. It is to be understood that one of the members just described and illustrated in Figure 3 of the drawings is employed for each of the bottom boards 22, 5 and is provided at a suitable point between its ends with rollers 36 which are adapted to engage the strap members 33 to swing the bottom boards 22 on their pivots and close the same.

10 Each of the legs 14 is provided with a vertical guide 37, and slidably mounted on said vertical guides is a transversely extending member 38, which is provided with perforations to receive said guides. Connected to the outer face of said transversely extending member 38 are links 39, the upper end of which is provided with an eye 40 adapted to engage one of the crank members 35, and secured to the transversely extending leg brace 25 is a resilient clip 41, which is adapted to engage said transverse member 38 to retain the same in its lowest position to prevent opening of the bottom boards 22.

15 25 The operation of the device is as follows: With the parts in the position shown in Figure 4 it will be seen that the bottom boards 22 of the body will be maintained in their closed position by reason of the transverse member 38 being secured against vertical movement in the guides 37. With the parts in this position the body of the wheel barrow may be filled with any suitable material. When it is desired to dump the material from the body it is only necessary to disengage the resilient clip 41 from the transverse member 38 whereupon the weight of the material on the bottom boards 22 causes them to rock on their pivotal point to the 30 35 40 position shown in Figure 5 where the material contained in the body is discharged therefrom.

From the foregoing it will be seen that the present invention provides a wheel barrow which may be loaded with material and transported from place to place as desired, said wheel barrow being capable of dis-

charging the material at the will of the operator in a simple and easy manner.

Having thus described the invention, what is claimed is:—

1. A dumping wheel barrow comprising a rectangular frame, supporting legs carried by the frame, a transversely extending brace connecting said legs, pivoted bottom boards 55 secured to the side members of the rectangular frame, and means pivotally mounted in the transversely extending leg brace and one of the transverse members of the frame and extending longitudinally of the said 60 pivoted bottom boards for moving them to open and closed position.

2. A dumping wheel barrow comprising a rectangular frame, legs depending from the frame, bottom boards pivotally carried 65 by the sides of the frame, and rockable crank shafts supported at one end in the frame and at their other ends in the transversely extending leg brace and carrying rollers engaging the lower faces of said 70 pivoted bottom boards to move the same to open and closed position.

3. A dumping wheel barrow comprising a frame, a pair of hinged bottom boards carried by the sides of the frame, depending 75 brackets carried by the forward end of the frame, a transverse bar supported below the rear of the frame, longitudinal crank shafts having their ends rotatably supported in the brackets and on the bar respectively, rollers carried by the cranks of the shafts and engaging in supporting relation to the bottom boards and means for rocking the shafts to swing the crank portions toward the hinged portions of the bottoms to permit 80 85 said bottoms to swing downwardly into dumping position.

In testimony whereof, I affix my signature, in the presence of two witnesses.

MICHAEL A. ZINNIEL.
